UNITED STATES PATENT OFFICE.

HARRISON RUSSELL LELAND AND WILLIAM SCHWEMLEIN, OF PARKERSBURG, WEST VIRGINIA, ASSIGNEES TO PARKERSBURG RIG & REEL COMPANY, OF PARKERSBURG, WEST VIRGINIA, A CORPORATION OF WEST VIRGINIA.

FLOATING DECK FOR OIL TANKS.

1,426,999.

Specification of Letters Patent. Patented Aug. 22, 1922.

Application filed May 12, 1921. Serial No. 469,021.

To all whom it may concern:

Be it known that we, HARRISON R. LELAND and WILLIAM SCHWEMLEIN, citizens of the United States, residing at Parkersburg, in 5 the county of Wood and State of West Virginia, have invented certain new and useful Improvements in Floating Decks for Oil Tanks, of which the following is a specification.

10 This invention relates to floating decks for oil tanks, and it comprises a body portion, a rim secured thereto, said rim being provided with a flange on its upper end, a series of plates arranged circumferentially of the 15 deck and contacting with the wall of the tank, said plates being extended upwardly and provided with flanges adapted to be arranged over the flange of said rim, levers connected to said plates adjacent their upper 20 ends, and springs secured to said levers to normally maintain said plates in engagement with the wall of the tank.

In a copending application Serial No. 468,058, filed May 9, 1921, we have disclosed 25 and claimed a floating deck for oil tanks in which a deck is provided which is surrounded by a plurality of plates adapted to contact with the wall of the vessel to prevent free circulation of air and gases. The subject matter of the present application broadly relates to the invention claimed in our copending application, but the invention herein disclosed and claimed differs in the details of construction from that disclosed in 30 our copending application.

In the present application, we provide a deck having an upwardly extending rim as in our copending application, the rim being provided with an upper flange. A series of 40 U-shaped plates adapted to contact with the wall of the tank, are supported on this flange, one of the arms of the U of each plate being provided with a flange adapted to be arranged over the flange of the rim to support 45 the plate and form a fulcrum therefor. An inwardly extending lever is attached to each plate, the free end of the lever having a spring secured thereto, adapted to turn the plate on its fulcrum and maintain it in engagement with the wall of the vessel.

50 In the accompanying drawings, we have shown one embodiment of the invention. In this showing:

Figure 1 is a side elevation of a tank showing the deck applied, parts being shown in 55 section, and,

Figure 2 is a detail perspective view of a portion of the tank and deck.

Referring to the drawings, the reference numeral 1 designates generally an oil tank 60 which may be formed of sections 2 secured to each other in any suitable manner, as at 3. A body of oil within the tank is indicated by the reference numeral 4.

The floating deck is adapted to rest upon 65 the body of oil, and comprises a body portion 5 to which an upwardly extending rim 6 is secured. The rim is provided with a lower flange 7, for the reception of suitable fastening means 8', passing through the 70 body portion of the deck. The rim is further provided with an upper flange 8.

The plates which are arranged around the circumference of the deck and contact with the walls of the tank are supported on the 75 upper flange 8 of the rim. As shown, each of the plates comprises a main outer section 9, having a base portion 10 and an inner section 11, forming a substantially U-shaped construction. An auxiliary plate 12 is secured to the upper end of the inner section 80 of the main plate by any suitable means. As shown, the plates are clamped, as at 13, to secure them to each other. The inner section is provided with a flange 14 on its upper end, which is adapted to rest on the flange 8 of the rim to support the plates 9 and 12. A lever 15 is secured to the plate 12 85 in any suitable manner, the free end of the lever being arranged at substantially right angles, as indicated at 16. A spring 17 is secured to the end of the lever, the opposite end of the spring being secured to the rim, as at 18. A quantity of gravel or other material may be arranged in the bottom of the 90 U-shaped plate, as indicated at 19. This material covers the spaces between adjacent plates to retard circulation of air, and other gases and vapors, thus reducing evaporation.

The operation of the device is as follows: 100

The deck is adapted to float on the top of a body of oil arranged within the tank, and the plates 9 are normally maintained in contact with the outer wall of the vessel by means of springs 17. The springs tend to 105 pull the horizontal portion 16 of the levers

downwardly and turn the U-shaped plates on the rim 8, as a fulcrum, causing the lower end of the plate 9 to be maintained in contact with the wall of the tank eliminating 5 free circulation of air and gases.

Thus, the plates are held in yielding engagement with the wall of the tank, and are permitted to adjust themselves to irregularities in the surface due to overlapping joints, 10 projecting rivets, and similar causes. As in our co-pending application, a construction is thus provided which reduces evaporation to a minimum, and reduces fire hazard. The deck sitting on top of the body of oil, 15 eliminates the space usually occupied by air, gases and vapors in the ordinary tank when the tank is partially filled with oil.

It is to be understood that the form of our invention herewith shown and described is 20 to be taken as a preferred example of the same, and that various changes in the shape, size, and arrangement of parts may be resorted to without departing from the spirit of the invention or the scope of the subjoined claims.

Having thus described our invention, we claim:

1. A floating deck for oil tanks comprising a body portion, an upwardly extending 30 rim secured thereto, said rim being provided with a flange on its upper end, a series of U-shaped plates pivotally supported on said flange and contacting with the wall of the tank, and means for retaining said plates in 35 contact with the wall of the tank.

2. A floating deck for oil tanks comprising a body portion, an upwardly extending rim secured thereto, said rim being provided with a flange on its upper end, a 40 series of U-shaped plates pivotally supported on said flange and contacting with the wall of the tank, levers secured to said plates and extending inwardly, and springs secured to said levers to retain said plates 45 in contact with the wall of the tank.

3. A floating deck for oil tanks comprising a body portion, an upwardly extending rim secured thereto, said rim being provided with a flange on its upper end, a 50 series of U-shaped plates arranged circumferentially of the body portion of the deck, the outer arm of said plates being adapted to contact with the wall of the tank, the inner arm being provided with a flange 55 adapted to rest on the flange on said rim to pivotally support said plates, and means

for retaining the outer arm of said plates in engagement with the wall of the tank.

4. A floating deck for oil tanks comprising a body portion, an upwardly extending 60 rim secured thereto, said rim being provided with a flange on its upper end, a series of U-shaped plates arranged circumferentially of the body portion of the deck, the outer arms of said plates being adapted to contact 65 with the wall of the tank, the inner arms being provided with flanges adapted to rest on the flange of said rim to pivotally support said plates, levers secured to the inner arms of said plates, and extending inwardly, 70 and springs secured to said levers to retain said plates in contact with the wall of the tank.

5. A floating deck for oil tanks comprising a body portion, an upwardly extending 75 rim secured thereto, said rim being provided with a flange on its upper end, a series of plates arranged circumferentially of the body portion and contacting with the wall of the tank, the lower ends of said plates 80 being extended inwardly and upwardly, a second plate secured to each of said plates and extending upwardly, said second plate being provided with a flange adapted to rest on the flange of the rim to pivotally support 85 said plates, and means for retaining said first plate in engagement with the wall of the tank.

6. A floating deck for oil tanks comprising a body portion, an upwardly extending 90 rim secured thereto, said rim being provided with a flange on its upper end, a series of plates arranged circumferentially of the body portion and contacting with the wall of the tank, the lower ends of said plates 95 being extended inwardly and upwardly, a second plate secured to each of said plates and extending upwardly, said second plate being provided with a flange adapted to rest on the flange of the rim to pivotally support 100 said plates, levers secured to said second plates and extending inwardly, and springs secured to said levers to normally maintain said first plates in contact with the wall of the tank.

In testimony whereof we affix our signatures in presence of two witnesses.

HARRISON RUSSELL LELAND.
